UNITED STATES PATENT OFFICE.

ABRAHAM MILLER AND JOHN N. KAILER, OF NEWARK, OHIO, ASSIGNEES
TO THE NEWARK MACHINE COMPANY, OF SAME PLACE.

CLOVER-HULLER.

SPECIFICATION forming part of Letters Patent No. 327,812, dated October 6, 1885.

Application filed February 11, 1884. Serial No. 120,380. (No model.)

To all whom it may concern:

Be it known that we, ABRAHAM MILLER and JOHN N. KAILER, of Newark, county of Licking, State of Ohio, have invented a 5 new and useful Improvement in Clover-Hullers; and we declare the following to be a full, clear, and exact description of the invention, such as will enable others skilled in the art to which it pertains to make and use it, reference being had to the accompanying drawings, which form a part of this specification—

Our invention consists of the combinations of devices and appliances, hereinafter specified, and more particularly pointed out in the claims.

15 In the manufacture of clover-hullers it has been customary to locate a large number of rubbers or hulling-teeth in the concave of the hulling-cylinder to operate in connection with the projecting teeth or rubbers on the surface 20 of the hulling-cylinder itself. It is, however, a matter of considerable difficulty to effect the separation of the small clover-seeds from the tough pods containing them, and this is especially true if the heads are not thoroughly 25 cured and perfectly dry. For this purpose we have heretofore employed detainers located between the lags of the huller-concave. Our present invention relates to the construction of the said detainers.

30 In the drawings Figure 1 represents a concave with the detainers between the lags. Fig. 2 represents the same in longitudinal section showing the relative position of the cylinder-teeth as they pass the detainers. Fig. 3 is a separate view, in side elevation, of one 35 of the detainers; Fig. 4, a cross-section of the same. Fig. 5 represents a variation in which the bottom of the throat is square; Fig. 6, another variation in which the bottom is rounded 40 and the ends square. Fig. 7 is a view of the tool employed in cutting the detainer. Fig. 8 is a view of a strip of material of a breadth sufficient for two detainers, showing the method 45 we pursue in cutting the detainer.

45 We have found that when these detainers are made with square edges at the top, these edges are apt to come in contact with the bases of the teeth, and so be soon destroyed or damaged. We have also found that when 50 the bottoms of the throats are made square they do not sufficiently detain the pods to effect a

thorough hulling, especially with damp clover; and again, when cut square at this point, the tongues of the detainers are apt to flex and soon break off across the lower edge. It is our 55 purpose to overcome these difficulties.

A represents the lags of the huller-concave; B, the detainers; C, the hulling-cylinder; D, hulling teeth or rubbers; E, rivets; F, washers.

G is the handle, and G' the blade, of the tool 60 by which the detainers are cut. The blade is of course made to conform to the peculiar shape of the throat of the detainer and the tongues.

The detainers we prefer to make of leather. 65 If the leather is of sufficient thickness, it may be made of a single ply of leather. We prefer usually, however, to make the detainers of two plies of leather glued together, and with rivets G passed through the tongues and 70 headed beyond the washer G'. In this way we are enabled to employ any part of a usual hide of leather, whereas if the detainer is made of a single ply of leather there is but a small part 75 of a hide that possesses leather of sufficient thickness. We also find the two plies to make a better and a stiffer detainer.

The detainer is composed of tongues B', with intervening throats B. The tongues may be made rounded at the top, so as to avoid contact with the adjacent bases of the teeth in passing, and when so made the throats may be either square or rounded at the bottom. So, also, when the throats are rounded at the bottom they serve the better to detain the seed 85 and to strengthen this part of the tongue, and when so made the extremities of the tongue may be made either square or round. We prefer, however, to make the extremities of the tongues and the bottoms of the throats both 90 rounded, and that is the way in which we usually employ them. A portion, B³, is preserved intact for insertion between the lags of the concave.

These detainers are not necessarily made of 95 leather. They may be made of rubber or of ordinary engine-packing, though we prefer leather. So, also, they may be made from a thin sheet of wood, with the tongues lying in the direction of the grain of the wood; or they 100 may be made of sheet metal.

These detainers may be cut by any suitable

mechanism; but we prefer to employ the tool G G' as a quick and ready means for doing the work, and we prefer to cut the lags from pieces of double the breadth required, since in that way there is no waste of the material.

We would also have it understood that instead of rounding the extremities of the tongues and the bottoms of the throats, they may be beveled off upon right lines instead of curved lines, the effect being in either case to build up the corners at the bottom of the throat, and to trim off the corners at the extremities of the tongues.

This device is designed more especially for 15 clover-machines, but is of course applicable in any kind of a seed-separator where a similar detainer may be employed.

The tool G G' may be made in a single piece. The blade of the tool is so shaped and is of such 20 a size that at one operation it cuts out one or more of the throats, and cuts at least half-way across the extremities of each of the two adjacent tongues.

We do not herein claim the cutting tool or 25 implement, as such constitutes the subject-matter of Letters Patent No. 302,759, issued to us July 29, 1884.

What we claim is—

1. A detainer for a clover machine or separator, consisting of a strip of material, B³, provided at its edge with tongues B' and throats B², the extremities of the tongues being dressed away at the corners and the bottoms of the throat left full at the corners, substantially as 35 and for the purposes described.
2. A detainer for a clover machine or separator, consisting of a strip of material, B³, provided at its edge with tongues B' rounded at their extremities, and throats B², rounded at the bottom, substantially as and for the purposes described.

40 rator, consisting of a strip of material, B³, provided at its edge with tongues B', rounded at their extremities, and throats B², rounded at the bottom, substantially as and for the purposes described.

3. A detainer for a clover machine or separator, consisting of a strip of material having tongues B' at its edge, said tongues being provided with rounded corners at their outer extremities, substantially as described.

4. A detainer for a clover machine or separator, consisting of a strip of material having tongues B' at its edge, the throats between the tongues being provided with rounded inner edges or bottoms, substantially as described.

5. The combination, in a detainer for a clover machine or separator, of two pieces of leather having tongues B' at their edges, with washers and rivets passing through the two 55 pieces of leather and headed on the washers, substantially as described.

6. A detainer for a clover machine or separator, consisting of two plies of material united together, with their adjacent surfaces in contact and formed integral with coincident tongues B' at their edges, said coincident tongues being in contact, substantially as described.

In testimony whereof we sign this specification in the presence of two witnesses.

ABRAHAM MILLER.
JOHN N. KAILER.
